UNITED STATES PATENT OFFICE.

ALBERT J. ERICKSON, OF BUFFALO, NEW YORK.

FOLDING UMBRELLA.

1,250,292.

Specification of Letters Patent. Patented Dec. 18, 1917.

Application filed December 14, 1914. Serial No. 877,117.

To all whom it may concern:

Be it known that I, ALBERT J. ERICKSON, a citizen of the United States, residing at Buffalo, in the county of Erie and State of New York, have invented certain new and useful Improvements in Folding Umbrellas, of which the following is a specification.

My invention relates to a folding umbrella and more particularly to that type of umbrella having a telescopic staff capable of being extended or contracted, and folding ribs so that the umbrella can be folded into compact space and be carried in a pocket.

Another object of my invention is to provide a folding umbrella of this type which is inexpensive to manufacture and which can be easily opened or closed like an ordinary umbrella, or folded so that it may be reduced in length not to exceed thirteen inches.

Another object of my invention is to provide folding ribs having joints, and means for locking the ribs in extended condition without injury to the japanned coating of the ribs.

Another object of my invention is the provision of means for retaining the sliding runner in the position it assumes when the umbrella is opened without interfering with the spring catch secured to the inner end of the tip section, and to so construct said spring catch that it may slide within the inner section and automatically project through openings in said inner section.

Further objects are to so construct the ribs that the cover may be attached thereto without any tendency to be drawn into the hollow of the ribs, and to otherwise improve on folding umbrellas of this type.

With these and other objects in view, the invention consists in the novel features of construction, and in the arrangement and combination of parts to be hereinafter described and more particularly pointed out in the subjoined claims.

In the drawings,—

Figure 1 is a vertical sectional view of an umbrella embodying my invention, the umbrella being open and ready for use with sufficient of the frame and cover shown to clearly illustrate the invention.

Fig. 2 is an elevation of my umbrella when completely folded.

Fig. 3 is a vertical sectional view on an enlarged scale, the staff of the umbrella being collapsed and the frame almost folded.

Fig. 4 is a vertical sectional view similar to Fig. 1, the parts being shown as they appear when the umbrella is almost closed.

Fig. 5 is an enlarged detailed view of the intermediate portion of a rib, and a stay or brace pivotally connected therewith, the parts being shown as they appear when the umbrella is opened.

Fig. 6 is an enlarged cross section through the staff and certain parts carried thereby, taken on line 6—6, Fig. 1.

Fig. 7 is an enlarged perspective view of the outer end of one of the stays or braces.

Fig. 8 is a cross section taken on line 8—8, Fig. 5, the cover being omitted.

Fig. 9 is a cross section through the slideable runner, taken on line 9—9, Fig. 10.

Fig. 10 is a side elevation of the slideable runner.

Fig. 11 is a detached perspective view of the catch ring or retainer slideable on the inner section of the staff.

Fig. 12 is an enlarged cross section, taken on line 12—12, Fig. 5.

Fig. 13 is an enlarged cross section taken on line 13—13, Fig. 5.

Fig. 14 is a similar cross section showing the outer rib member nested in the inner rib member with the covering material between the two.

Fig. 15 is a side elevation of the intermediate portion of a rib and its associate brace and stay.

Fig. 16 is a detached perspective view of the outer end of the inner member of one of the ribs.

Fig. 17 is a face view of the intermediate portion of a rib and the adjacent end of the brace connected thereto.

Fig. 18 is an enlarged sectional view of a portion of the tip section and the adjacent end of the inner section of the staff.

Referring by numerals of reference to the drawings, 12 designates the umbrella staff which is formed of metal tubing and constructed of hollow sections of gradually in-

creasing size so that one section is slideable within another and when telescoped, as shown in Fig. 3, the staff will not exceed thirteen inches in length. This staff may be 5 said to comprise an outer or handle section 13, an intermediate section 14, an inner section 15, and a tip section 16. Each section is retained against rotary movement with respect to adjoining sections in any approved 10 manner, and the inner section 15 and intermediate section 14 have spring actuated catches 17 at their outer ends which extend through openings in said section and are respectively adapted to extend into or through 15 openings 18 in the surrounding sections when the staff is extended. In this manner the sections of the staff are rigidly held together at a length corresponding to that of a staff of an ordinary umbrella. When it is desired to 20 collapse the staff, it is simply necessary to depress the catches 17 and force the sections of the staff together so that they assume the positions shown in Fig. 3. Near the inner end of the inner section 15 a notched rib 25 holding flange 19 is secured to which the inner ends of the ribs 20 are pivotally attached in the usual manner. Applied to the ribs is the usual cover 21 and a cap 22 is threaded or otherwise secured to the inner 30 extremity of said inner section and bears against the cover so as to confine the same between said cap and notched rib holding flange 19.

The tip section 16 has arranged therein a 35 spring catch 23 which has a fulcrum protuberance 24 at an intermediate point bearing against the inner surface of said section, a catch lip 25 adapted to pass through an opening 26 in said tip section and enter 40 an opening 27 in said inner section, and a finger piece 28 which extends out through an opening 29 by means of which the spring may be depressed to disengage said catch lip from the opening 27. When the tip is 45 extended, as shown in Figs. 1 and 4, the catch lip 25 is entered in the opening 27, and in order to telescope said section it is necessary to exert pressure inwardly against the finger piece 28 to disengage said lip from 50 its receiving opening and then force the tip section inwardly into the position shown in Fig. 3. During the time said tip section is being forced into the adjacent section of the staff and while retained in telescoped position, the spring catch exerts its pressure 55 against the inner surface of said inner section but does not become locked, since these lips do not register with any openings in the inner section. Upon drawing the tip section outwardly, the spring catch recovers itself as soon as the catch lip 25 is brought in line with the opening 27 of said inner section and automatically locks the tip section against lengthwise movement.

60 65 Fastened to the inner end of the tip sec-

tion is a spring catch 30 fulcrumed against the inner surface of the inner section, as at 31, and having two catch lips 32, 33. Said catch lips are spaced apart, and when the tip section 16 is extended, are adapted 75 to extend through openings 34, 35, respectively, in the inner section 15 of the staff, as clearly shown in Fig. 1. When, however, the tip section is telescoped, the catch lips 32, 33, are confined within the inner section 75 and bear against the inner surface of the latter, as shown in Fig. 3.

Slidable on the staff is a runner 36 to which are pivotally secured the inner ends of stays or braces 37, said stays or braces 80 being pivotally connected to the ribs 20, as at 38. The runner is of a size to receive the inner end of the outer or handle section 13 of the staff when the latter is telescoped, as shown in Fig. 3, and it has an enlargement 85 or swell 39 in line with the catch lips 32, 33 of the spring catch 30 secured to the inner end of the tip section. When the runner surrounds the catch lips 32, 33, this enlargement or swell receives the catch lip 33 and 90 prevents depression of the same, which would cause both catch lips 32, 33, to recede into the intermediate staff section and permit the runner to slide beyond the point at which it is intended to be retained. This swell or enlargement of the runner is particularly desirable owing to the fact that the runner is somewhat larger than the inner section and has a certain amount of play around the same which would permit the catch lip 33 100 to be depressed unless additional space were provided by enlarging the runner at the point directly over said catch lip so that even though the runner were moved laterally on the staff when in the position it 105 assumes when the umbrella is opened, it cannot come in contact with said catch lip and cause the same to be depressed. The runner is retained in position on the inner section 15 when the umbrella is opened, by 110 means of a catch ring or retainer 40 which is slidable on the inner section 15 of the staff only. Said catch ring or retainer has an outstanding flange 41 at its inner end and curved spring fingers 42 capable of being 115 pressed inwardly against said section, and it is retained between the catch lips 32, 33, of said spring catch or retainer when the umbrella is open. At such times the runner 36 frictionally engages said ring and is 120 retained thereby against movement lengthwise on the staff. In order to overcome all tendency of the runner moving lengthwise under wind pressure, the stays or braces 37 are arranged at a right angle to the staff 125 when the umbrella is open.

By the use of the spring catch 30 secured to the inner end of the tip section, the catch ring or retainer 40 and the runner 36, a full length tip section can be employed, and 130

during the operation of closing the umbrella, as shown in Fig. 4, it is simply necessary to grasp the runner and pull outwardly thereon, the catch ring and retainer 40 remaining in position between the two catch lips 32, 33, of the spring 30. When the runner 36 is moved outwardly on the staff to close the umbrella, it is sprung over a pair of lugs 43 formed on the outer or handle section of the staff, and to permit of this the runner is split lengthwise at diametrically opposite points, as at 44, and it is also provided with a flaring outer end 45 and an internal groove 46 into which the lugs 43 enter, thus holding the umbrella closed.

Each of the ribs 20 comprises two parts or members 47, 48, which are pivotally connected together and to the stays or braces 37, associated therewith by the pivot 38 common to all. In cross section the ribs and braces are of channel shape and they are made of a size so that the outer member 47 of each rib folds into the inner member 48, and the folded rib members fold into the common operating stay or brace, thus making a compactly folding umbrella.

The inner end of each outer rib member 47 is reinforced, as at 49, and it has secured thereto a spring catch 50 formed of wire and comprising a shank 51 rigidly secured to said member, and a spring loop 52, against which the outer extremity 53 of the inner rib member is adapted to impinge when the rib is unfolded. As is common in umbrella construction, the ribs and stays or braces are japanned, and as the loops 52 engage only the outer edges of the inner members 48 of the ribs, the wearing away of the japanned surface is completely eliminated. Thus the tendency to rust due to the metal being exposed is reduced to the minimum.

Between the cover 21 of the umbrella frame and the joints of the ribs, joint pads 54 are inserted, and when the ribs are folded the spring loops 52 project outwardly far enough to make it impossible for the joint pads to interfere with the locking of the rib members. When said pads work around the sides of the ribs, as shown in dotted lines in Fig. 12, the loops 52 prevent the curling of the pads underneath the outer members of the ribs, as they would do in the absence of such loops; and when unfolding the members of the ribs, the pads would be forced between the sides of the rib sections and become ragged and torn, which said loops now guard against.

The spring loops or catches 52 are so constructed that they lock easily of their own accord when opening the umbrella, and unlock at their maximum strength when folding the umbrella. They also give additional strength for the rib at the joints by

reason of the reinforcements in which said springs are fastened and have sufficient spring to overcome any slight wear on the end edges of the inner members, due to friction.

In order to employ these spring loops or catches, it is necessary that the outer end of each brace be provided with an elongated opening 55 so that when closing the umbrella the loop or catch will extend through said opening. This opening also permits the umbrella to be folded compactly.

The outer end of the inner member of each rib has its side walls flared outwardly, as at 56, and these flared portions serve to prevent the inner members of the ribs passing through the slots in the braces, which would cause unlocking of the ribs, and under such conditions the user would always be uncertain as to the umbrella opening correctly. These flares also retain the braces 80 a trifle out of alignment with the ribs so as to prevent the umbrella from sticking when opening the same, thus making it unnecessary to shake or strain the umbrella which would in time tend to weaken the same.

Near the outer end of each inner member of the rib, apertures 57 are provided and the cover 21 is sewed to the ribs at these points by a loose thread connection, the thread being sewed through the cover at the seam, as at 58, and passed through the apertures from the inner side of the rib and the ends tied together, as at 59, on the under or outer side of the rib. It is to be noted

that the rib is curved on its under or outer side, and that the thread is exposed only within the region between said apertures so that the braces and ribs may swing relatively without the thread rubbing against any portion thereof. Moreover, the connection made between the cover and rib at this point by means of the thread being loose, permits the cover to stretch smoothly over the edges of the channel-shaped rib and when the outer rib members are folded into the inner members, the cover can enter the inner members without straining the thread connection.

It is desirable that the umbrella be closed before attempting to fold the same, and when in closed position pressure is exerted against the outer members of the ribs from within, which causes the joints to break and the said outer members to fold onto the inner members. The runner 36 is then taken hold of and moved to engage the spring catch or retainer 40. The staff is then collapsed by depressing the catches 18 and exerting force lengthwise on the handle section and intermediate section, and when the intermediate section is moved inwardly, the inner end thereof enters the runner 36, engages the catch lip 33 of the spring catch

30 and depresses said lip so as to cause both catch lips 32, 33, to move inwardly into the inner section of the staff. Further thrust on the staff sections causes the spring catch or 5 retainer 40 to move inwardly against the notched rib-receiving flange 19, after which the inward or telescoping movement of the outer handle section of the staff may be completed and the runner moved upwardly 10 to slide onto the spring catch or retainer 40, previously moved inwardly by the inner end of the intermediate section 14. The tip section 16 may then be forced into the staff by depressing the finger piece 28 of 15 the spring catch 23 and exerting pressure against the outer end of said section. The loose portions of the cover may now be smoothly rolled around the folded ribs and, by means of the usual band, retained in 20 folded position.

Having thus described my invention, what I claim is,—

1. In a folding umbrella, a frame having folding ribs, each rib comprising an inner 25 and an outer member pivotally connected together, each of said members being of channel shape in cross section and reversely arranged so that the channels thereof face in opposite directions, the inner end of the 30 outer member being reinforced and provided with a spring loop adapted to engage the outer edge of the inner member.

2. In a folding umbrella, a frame having folding ribs and braces connected to said 35 ribs, each rib comprising an inner member and an outer member pivotally connected together and to the co-acting brace by a pivot common to the three, said brace having an elongated slot and said outer 40 member having a spring loop adapted to engage the outer edge only of said inner member, said loop being adapted to extend through the slot of said brace when the frame is closed.

45 3. In a folding umbrella, folding ribs comprising each an inner and an outer member pivotally connected together, said rib members being channel-shaped in cross section and reversely arranged so that the 50 channels thereof face in opposite directions, said outer member having its inner end reinforced and provided with a spring catch having a loop adapted to engage the outer end of the inner member, covering material secured to said folding ribs, and a joint pad between the joints of each rib and said covering material, said loop being arranged to prevent the joint pad curling around the rib.

60 4. A folding umbrella having folding ribs and braces connected to said ribs, each of said ribs comprising an inner member and an outer member, a pivot connecting said inner and outer members together and with

the brace at a point common to all, said rib 65 members and brace being channel shaped in cross section, the rib members being reversely arranged so that the channels thereof face in opposite directions, the outer member of each rib being adapted to fold 70 into the inner member and the inner member being adapted to fold into said brace, said brace being provided with an elongated opening at its outer end to provide two arms straddling the rib members, means 75 for retaining the rib members in open or extended position, and means at the outer end of the inner member to maintain the brace in a position out of line with the rib when the umbrella is closed. 80

5. An umbrella having a folding frame comprising folding ribs and braces, each rib comprising an outer rib member and an inner rib member, said rib members being pivotally connected together and to 85 their co-acting braces by a pivot common to the three, said rib members and braces being of channel formation in cross section, the rib members being reversely arranged so that the channels thereof face in opposite 90 directions, the outer rib member of each rib being adapted to fold into the inner rib member and the inner rib member being adapted to fold into the coacting brace, said brace having its outer end cut away between 95 its sides to provide an elongated opening and said inner rib member having its sides flared at its outer extremity to be engaged by the sides of said brace when the umbrella is closed, thus retaining the braces out of 100 line with the ribs and preventing binding of the parts when opening the frame.

6. An umbrella having a folding frame comprising folding ribs and braces connected to said ribs, each rib comprising two 105 rib members pivotally connected together and to their co-acting brace, said rib members and brace being of channel shape in cross section and the brace being cut away at its outer end between its sides to provide 110 an elongated opening, the inner member of each rib having apertures near its outer end arranged at opposite sides of the longitudinal center of said member, covering material extending over said rib and having a thread 115 connection therewith, the thread of said connection being passed through said covering material, into the inner rib member, through said apertures and the ends thereof tied together outside of said rib member at 120 a point between said apertures, the thread forming said connection being slack to prevent the cover being drawn into the hollow of the rib member, said rib member being adapted to fold into said brace without said thread connection coming in contact with said brace. 125

7. A folding umbrella having channel-

shaped ribs, and a cover stretched over said ribs and connected thereto, said cover being attached thereto by loose connections passing outwardly through the channels of said 5 ribs so as to prevent the cover being drawn into the channels of said ribs when the umbrella is opened.

In testimony whereof I affix my signature in presence of two witnesses.
